G. EGLOFF

HEAT INTERCHANGER

Filed Jan. 6, 1921

UNITED STATES PATENT OFFICE.

GUSTAV EGLOFF, OF INDEPENDENCE, KANSAS, ASSIGNOR TO UNIVERSAL OIL PRODUCTS COMPANY, OF CHICAGO, ILLINOIS, A CORPORATION OF SOUTH DAKOTA.

HEAT INTERCHANGER.

Application filed January 6, 1921. Serial No. 435,321.

To all whom it may concern:

Be it known that I, GUSTAV EGLOFF, a citizen of the United States, residing in the town of Independence, county of Montgomery, and State of Kansas, have invented certain new and useful Improvements in Heat Interchangers, of which the following is a specification.

This invention relates to improvements in heat interchangers, and is adapted to be used either as a preheater, condenser or dephlegmator or serve at the same time both as a condenser and preheater.

The object of the invention is to secure the highest efficiency in heat interchangers by causing the raw oil to travel perpendicular to the flow of hot vapors or hot oil. The following covers a description of the heat interchanger, as shown in the drawing, in which the single figure is a view, partly in side elevation and partly in vertical section, of my improved heat interchanger.

Referring in detail to the drawing, 1 designates a cylindrical shell having two compartments 2 and 3, one at each end. 4 and 5 represent tube plates in which are expanded tubes 6. At right angles to tubes 6 are supported partitions 7 forming compartments 7 through which the cooling liquid travels from header 8 by means of pipe connections 9 connecting header 8 and compartment 7 to one another. 10 represents pipe connections from compartment 7, carrying the cooling liquid by means of header 11 through pipe 12 controlled by valve 13 to a system (not shown).

Pump 14 forces the cooling liquid controlled by valve 15, to the compartments 7 which are perpendicular to pipes 6. The hot vapors or hot oil from the still (not shown) pass by means of pipe 16 controlled by valve 17 into compartment 3 and up through pipes 6 to compartment 2 and out by means of pipe 18 to a system (not shown). The heat interchanger may be utilized as a dephlegmating apparatus, such as is used in the cracking of hydrocarbon oils and when employed for this purpose, the vapors from the cracking system pass up through a series of pipes as shown in the drawing while perpendicular to the flow of heated vapors to the cracking still a cool-

ing liquid such as raw oil, water or the like flows around the tubes at right angles to the direction of flow of the heated vapors, 55 a very high heat interchange efficiency is obtained. I particularly stress the fact that the cooling liquid is always travelling at right angles or perpendicular to the flow of the hot vapors and a much smaller 60 amount of cooling fluid is necessary over any other heat interchanger, of which I am aware.

The heat interchange as described is particularly efficient when heated oil residuums 65 from the atmospheric distillation of petroleum or other hydrocarbons are to be cooled. When using the heat interchanger for hot oil, water may be used as the cooling agent and we have found that this system is more 70 efficient than any system thus far devised. In using this heat interchanger practically we have utilized as cooling liquid a hydrocarbon oil such as gas oil and found that we could bring the temperature of the cooling liquid to upwards of 400 degrees F., from the hot residuum oil leaving the cracking system, and this hot gas oil was utilized directly in the cracking system as 75 the raw oil to be converted into gasoline. 80

I do not limit myself in this invention to its use in the petroleum art, either as a dephlegmating apparatus for the fractionation of hydrocarbon vapors or as a heat interchanger for the cooling of heated oil but it 85 may be efficiently used as a heat interchanger where there is a different temperature between the cooling material and the heated material.

I claim as my invention:

1. In a heat interchanger for treating petroleum oils and vapors, comprising a main body portion, a plurality of vertically arranged tubes positioned within the main body portion, means for passing oil 95 through said tubes, said main body portion being provided with a plurality of transversely extending partition members forming a multiplicity of closed fluid receiving chambers, and means for individually passing oil through each of said chambers transversely to the flow of oil through said vertically arranged tubes.

2. In a heat interchanger for treating

petroleum oils and vapors, comprising a main body portion, a plurality of vertically arranged tubes positioned within said main body portion, means for passing hot oils or gases through said tubes, said main body portion being provided with a plurality of transversely extending members forming a multiplicity of fluid receiving chambers, a vertically arranged header on each side of

said main body portion, tubes connecting said headers to said chambers, and means for forcing oil of a relatively low temperature through one of said headers and its connecting tubes through the said chambers to cool the said oils and vapors in the vertically arranged tubes, and means for drawing off the oil from the adjacent header.

GUSTAV EGLOFF.
